POLE HOLDER

Julian W. McManus, 3733 Delmas Terrace,
Los Angeles, Calif.

Filed May 14, 1962, Ser. No. 70,100

Term of patent 14 years

(Cl. D88—3)

FIG. 1.

FIG. 2.

FIG. 3.

FIG. 4.

FIG. 5.

FIG. 6.

FIGURE 1 is a perspective view of a pole holder showing my new design, a part of the pole being shown in dotted lines for illustrative purposes only;

I claim:

The ornamental design for a pole holder, substantially as shown and described.
